UNITED STATES PATENT OFFICE.

JACOB FLOERSHEIM, OF CHICAGO, ILLINOIS.

DESIGN FOR AN ORNAMENT.

No. 38,653.

Specification for Design.

Patented July 9, 1907.

Application filed June 8, 1907. Serial No. 378,033. Term of patent 3½ years.

To all whom it may concern:

Be it known that I, JACOB FLOERSHEIM, a citizen of the United States, residing at Chicago, in the county of Cook and State of Illinois, have invented a new, original, and ornamental Design for Ornaments, of which the following is a specification, reference being had to the accompanying drawing, forming part thereof.

The figure is a plan view showing my new design for an ornament.

I claim:

The ornamental design for an ornament as shown.

JACOB FLOERSHEIM.
